WINDOW CLEANER

Filed June 8, 1931

R. TRANE.

Inventor

By *David O. Barnell*

Attorney

UNITED STATES PATENT OFFICE

RAYMOND TRANE, OF OMAHA, NEBRASKA

WINDOW CLEANER

Application filed June 8, 1931. Serial No. 542,860.

My invention relates to devices for cleaning windows and the like, and it is the object thereof to provide a simple, inexpensive, compact and convenient device which may be used for both washing and drying windows or other glass surfaces. A particular object of my invention is to provide a window cleaning device in which the handle and the holder which carries the washing and wiping elements are connected pivotally to enable the handle to be placed in operative relation to either of said elements, and also to allow the use of the device in positions at which a fixed handle would interfere with its use. A further object is to provide a device of this character in which the handle and the head or holder for the washing and wiping elements may be placed in an alined relation, whereby to occupy a minimum storage space, and thus especially adapting the device to be carried as a motor-vehicle accessory. A further object of my invention is to provide a simple and inexpensive holding means for a pair of parallel, oppositely extending cleansing elements.

the strips 6 and 7, and said side portions 10 are slightly bowed so as to be convergent toward their edges, whereby to clamp upon and securely retain the strips 6 and 7 between them. At the center of the holder, intermediate the ends of the swaged portions 8 and spaced similarly to the adjoining parts of the side portions 10, are portions 11 which are perforate to receive the pin or rivet 12 by which the handle is pivotally connected with the holder. The handle is formed by an integral strap or strip of metal, bent intermediate its ends to an approximate U-shape, the ends 13 straddling the holder and being pivotally connected therewith by the rivet 12. The sides 14 of the U-portion of the handle are swaged to a concavo-convex formation, as best shown in Fig. 5, whereby to stiffen said portions and to provide a rounded grip for the hand of the user. The length of the handle is slightly more than half the length of the holder, whereby the holder may swing freely between the spaced sides of the handle, and the latter may thus extend from either side of the holder, to present for use either of the strips 6 or 7 at the side opposite the handle.

In the accompanying drawings Fig. 1 is a plan view of a device embodying my invention, Fig. 2 is a transverse section on the line 2-2 of Fig. 1, Fig. 3 is a transverse section on the line 3-3 of Fig. 1, Fig. 4 is a detail longitudinal section on the line 4-4 of Fig. 1, and Fig. 5 is a detail section of a portion of the handle, on the line 5-5 of Fig. 3.

In carrying out my invention according to the illustrated embodiment thereof, I provide a rectangular strip 6 of porous absorbent material such as felt, which forms the washing element of the device, and a rectangular strip 7 of resilient material such as soft rubber, which forms the wiping or drying element of the device, said washing and wiping elements projecting from the opposite longitudinal edges of a flat rectangular holder. Said holder is formed by an oppositely disposed pair of metal plates having inwardly swaged intermediate abutting portions 8 secured together by suitable means such as the eyelets or hollow rivets 9. The opposite longitudinal side portions 10 of the holder-plates are spaced apart to receive the inner portions of

the strips 6 and 7, and said side portions 10 are slightly bowed so as to be convergent toward their edges, whereby to clamp upon and securely retain the strips 6 and 7 between them. At the center of the holder, intermediate the ends of the swaged portions 8 and spaced similarly to the adjoining parts of the side portions 10, are portions 11 which are perforate to receive the pin or rivet 12 by which the handle is pivotally connected with the holder. The handle is formed by an integral strap or strip of metal, bent intermediate its ends to an approximate U-shape, the ends 13 straddling the holder and being pivotally connected therewith by the rivet 12. The sides 14 of the U-portion of the handle are swaged to a concavo-convex formation, as best shown in Fig. 5, whereby to stiffen said portions and to provide a rounded grip for the hand of the user. The length of the handle is slightly more than half the length of the holder, whereby the holder may swing freely between the spaced sides of the handle, and the latter may thus extend from either side of the holder, to present for use either of the strips 6 or 7 at the side opposite the handle.

When the handle of the described device is swung to a position at which it is alined longitudinally with the head or holder, as indicated by the dotted lines *a* in Fig. 1, the device will occupy a minimum of space, and may thus be conveniently carried, or stored in a limited space when not in use. In the normal use of the device, the handle is positioned substantially at right angles with the head or holder, as shown in Fig. 1, wherein the absorbent strip 6 is presented for use in washing the surface to be cleansed. For the removal of loose dry material such as dust, the strip or element 6 may be used dry, as a brush to dislodge such non-adherent material from the surface to be cleansed. For adherent materials, the porous and absorbent strip 6 may be suitably moistened, and used to rub and loosen the material, after which the holder may be reversed relative to the handle, and the rubber strip 7 used as a squeegee to wipe the moisture from the surface. For reaching into corners or around

obstructions, the handle may be held in a diagonal relation to the head or holder, as suggested by the dotted lines *b* and *c* in Fig. 1, and when the handle is held in such a diagonal position, the pressure applied thereto by the hand is partly lateral thereof instead of being principally longitudinal as when the parts are in the normal right-angled relation.

10 It will be seen that by the pivoting of the handle to the center of the holder, the pressure upon the working edges of the strips 6 or 7 will be uniform throughout the length thereof, and the rubbing or wiping operations for cleansing the glass surfaces may be rapidly and effectively performed, by reason of the entire length of the working edges being fully utilized.

Now, having described my invention, what 20 I claim and desire to secure by Letters Patent is:

25 1. In a device of the class described, a holder comprising a symmetrical pair of oppositely disposed rectangular plates having the longitudinal side portions thereof spaced apart and bowed convergently toward their edges, intermediate longitudinal portions of said plates being swaged inwardly to abutting relation, means fixedly securing said inwardly swaged portions together, and a substantially U-shaped handle straddling said holder and having its ends pivotally connected therewith at the center thereof, said handle being adapted to swing about the pivotal axis 30 past the ends of the holder.

35 2. In a window cleaning device, a holder comprising a symmetrical pair of oppositely disposed rectangular plates having the longitudinal side portions thereof spaced apart and bowed convergently toward their edges, intermediate longitudinal portions of said plates being swaged toward each other, strips of yielding material disposed between the convergently bowed side portions and having 40 working edges projecting oppositely from the longitudinal edges of the holder-plates, means for securing in abutting relation the inwardly swaged intermediate longitudinal portions of the plates to clamp said strips between the convergently bowed side portions, and a U-shaped handle straddling said holder-plates and having its ends pivotally connected therewith at the center thereof, said handle being adapted to swing about the 45 pivotal axis past the ends of the holder whereby to assume any desired angular relation to said working edges in the plane of the holder-plates.

RAYMOND TRANE.
